ARTICLE FORMING APPARATUS

John S. Stull, Chicago, Ill., assignor to Western Electric Company, Incorporated, New York, N. Y., a corporation of New York

Application March 18, 1944, Serial No. 527,123

8 Claims. (Cl. 82—20)

1

This invention relates to article forming apparatus and more particularly to an apparatus for turning surfaces of armature cores.

In the manufacture of armature cores, it has been the practice heretofore to form the cores substantially to the proper configuration and, thereafter, to cut the outer partially circular surfaces thereof in a lathe so that the amount of metal in each leg of the armature core will be as closely the same as in the other leg as is possible. In so forming armature cores, the legs of the core are engaged alternately by the cutting tool and as the cutting tool bites into the core, there is a tendency for the blank being cut to shift with respect to the tool. Thus, where highly accurate cores were desired, it was necessary, after the lathe operation, to grind the surfaces of the core to remove the inequalities formed on the surfaces thereof in the lathe.

It is an object of the present invention to provide a simple, inexpensive and effective apparatus for expeditiously forming articles.

In accordance with one embodiment of the invention, a blank holding fixture is provided for holding an armature blank to be machined in a drill press. The blank holding fixture is provided with a series of blank engaging elements, all shiftable under control of a single manipulative device, to press outwardly against internal surfaces of the core blank and to press axially of the core blank, thus to exactly center the core with respect to the fixture. On its upper end, the blank holding fixture has a bearing which engages the interior surfaces of a tubular tool holding member, thereby to assure that the tool holding member will be held coaxially with the blank held by the blank holder during the machining of the outer surfaces of the blank by the tools.

A complete understanding of the invention may be had by reference to the following detailed description when considered in conjunction with the accompanying drawings, wherein

Fig. 1 is a side elevational view on a relatively small scale of a drill press equipped with mechanism comprising one embodiment of the present invention;

Fig. 2 is a fragmentary front elevational view on the same scale as Fig. 1 and showing the portion of the drill press embodying the present invention;

Fig. 3 is an enlarged transverse vertical sectional view taken centrally through the fixture and a portion of the head of the drill press and showing a blank after it has been machined and also showing the tubular tool-holding fixture in its upper or retracted position;

Fig. 4 is a horizontal sectional view taken substantially along the line 4—4 of Fig. 3 in the direction of the arrows;

2

Fig. 5 is a horizontal sectional view taken substantially along the line 5—5 of Fig. 3 in the direction of the arrows;

Fig. 6 is a sectional view taken through the centerline of the tool-holding fixture and the blank-supporting fixture and showing the tools in their lowermost positions;

Fig. 7 is a plan view of a finished armature core machined in the apparatus disclosed in Figs. 1 to 6; and

Fig. 8 is a side elevational view of the core shown in Fig. 7.

As shown most clearly in Fig. 1, the drill press includes a standard 10, which extends from a base 11 of the drill press to support a head portion 12. Rotatably mounted in the head portion 12 is a spindle 13 having fixed thereto a pulley 14 adapted to be driven by a belt 15. As is usual in drill presses of this type, a manually operable spider or hand wheel 16 is provided for raising and lowering the reciprocable portion 18 of the drill spindle. The spindle 18, when it rotates, will, of course, drive the reciprocable portion 18 thereof and upon manipulation of the spider 16, the portion 18 may be lowered from the position shown in Fig. 1 and may be raised therefrom. Suitably attached to the reciprocable portion 18 of the spindle 13 is a tool-holding tube 19, which, as shown most clearly in Figs. 3 and 6, has a plurality of cutting or turning tools 20 suitably attached to it, for example, by a retainer ring 21 having a tapered wall 22 and a threaded portion 23, the threaded portion being threaded onto a flange 24 formed integrally with the tube 19. The tube 19 is slidable and rotatable in a bearing 25 seated in a bracket 26. The bracket 26 is provided with a tapered collar 27 suitably attached thereto or formed integrally therewith and the bearing 25 is seated in this collar 27 by means of retainer rings 28 and 29 threaded onto the bearing 25 and engaging an undersurface of the bracket 26 and the upper surface of the collar 27. The bearing 25 has its outer surface tapered so that it will properly seat within the collar 27 to guide the tube 19 in its reciprocation and rotation.

The bracket 26, as pointed out hereinbefore, is suitably mounted upon the base 11 and, in addition to supporting the bearing 25 on its upper surface, serves to support a blank-holding fixture 35 designated generally by the numeral 35. The blank-holding fixture 35 comprises a support block 36 welded or otherwise suitably secured to the base of the bracket 26 and having mounted in it an upright member 37, which is secured in the block 36 by means of machine screws 38—38. In addition to receiving the upright member 37, the support block 36 has slidably mounted therein a clamp actuator 39, as seen most clearly in Fig. 6. The clamp actuator is freely slidable in the block 36 and is slotted at its lower end, as shown at 40,

to receive a lever 41, which is pivotally mounted in the member 37, being mounted upon a pivot pin 42.

As will be seen most clearly in Fig. 5, the support block 36 is cylindrical in configuration and the bottom portion of the upright member 37 is also substantially cylindrical, being slotted, as shown at 43, to receive the clamp actuator 39. Slidably mounted in a central aperture 44 in the bottom portion of the upright member 37 is a sleeve 45, in which there is, in turn, slidably mounted a push rod 46. The push rod 46 is mounted for limited movement in the sleeve 45 and has a notch 47 cut therein to receive a pin 48 mounted in the sleeve 45, thereby to prevent the push rod 46 from rotating. The lower end of the push rod 46 has a head portion 49 formed on it and the shank of the push rod is surrounded by a compression spring 50, which engages the lower end of the sleeve 45 and the upper surface of the head 49 to urge the push rod 46 downwardly with respect to the sleeve 45 and into engagement with a camming portion 51 of a shaft 52. The shaft 52 is journaled in the support block 36 and is provided, as shown in Figs. 1 and 2, with an actuator handle 53, the shaft 52 passing through an aperture 54 in the bracket 26. The camming portion 51 of the shaft 52, in addition to engaging the head portion 49 of the push rod 46, also engages a camming surface 55 on the lever 41. As pointed out hereinbefore, the shaft 52 is journaled in the support block 36. However, it should be noted that the apertures 56 and 57, in which the shaft 52 is journaled, are substantially oval in shape and that the aperture 58 in the member 37 is also substantially oval, thereby to permit the shaft 52 to be rotated while permitting it a limited amount of movement vertically. The purpose of this limited movement of the shaft 52 will become apparent as the description progresses. Positioned in a slot 59 formed in the bottom of the member 37 is a leaf spring 60, which is fixed to an undersurface of a slot 61 formed in the support block 36. This leaf spring normally urges the lever 41 to rock counter-clockwise and, therefore, normally urges the clamp actuator 39 upwardly.

Extending upwardly from the body portion of the upright member 37 is a post 70 having an enlarged head portion 71, from which there extends a threaded shank 72. The shank 72 has a pre-loaded anti-friction bearing 73 fixed to it by means of a retainer nut 74, which holds the anti-friction bearing and a gasket 75 in place on the post 70. The gasket 75 is clamped between a pair of gasket retaining rings 76 and 77, which are interposed between the bottom of the anti-friction bearing 73 and the head portion 71. The anti-friction bearing 73 is slidable within the tube 19 and has its outer race relieved to tend to reduce the friction between the inner wall of the tube 19 and the post 70 and also tends to properly locate the cutting tools 20 with respect to a blank 78 held on the blank-holding fixture 35. The clamp actuator 39 has a clamp 79 pivotally mounted on it by means of a pivot pin 80, which extends through the clamp 79 and is fixed in upstanding lugs 81—81 formed on the clamp actuator 39. The clamp 79 cooperates with a clamping lug 82 formed integrally with the post 70, thus to serve as a guide for the upper end of the sleeve 45 and for the lower end of a sleeve 83 positioned in direct vertical alignment with the sleeve 45. The sleeves 45 and 83 are of similar construction in that the upper end of the sleeve 45 is provided

with a notch which forms positioning surfaces 84 and 85 which cooperate with similar positioning surfaces 86 and 87 on the sleeve 83 (Fig. 6) to engage the central portion 88 of the blank 78. The sleeve 83 is slidable in the upper end of the upright member 37, being normally urged downwardly with respect to the head 71 of the upright member 37 by a compression spring 89, which engages the upper end of the sleeve 83, and a head portion 90 of a push rod 91, similar to the push rod 46. The push rod 91 is slidable within the sleeve 83 and the sleeve 83 is provided with a slot 92, into which extends the reduced end 93 of a set screw 94, threaded into the post 70. In this manner, the amount of movement of the sleeve 83 is limited and, correspondingly, the amount of movement of the push rod 91 is also limited.

Set into a head portion 101 of the sleeve 45, as shown most clearly in Figs. 3 and 5, are a pair of positioning members 102 and 103, which are retained in the head portion 101 by retainer pins 104 and 105, which extend through slots 106 and 107 in the positioning members 102 and 103, respectively. Otherwise, the positioning members are freely slidable in slots 108 and 109 formed in the head portion 101. In a manner similar to that just described, the sleeve 83 is provided with two positioning members 112 and 113 positioned in slots 114 and 115 and retained in place by pins 116 and 117 (Figs. 3 and 4), which extend through slots 118 and 119, respectively, in the positioning members 112 and 113. The inner ends of the positioning members 102, 103, 112 and 113 are tapered to be engaged by the push rods 46 and 91, which are provided with cooperating tapered ends or cam faces adapted to engage the tapered inner ends of the positioning members and to cam them outwardly into engagement with the sides 120—120 of the armature blank 78.

In the operation of the apparatus, an armature blank 78, which is to have the portions 121, as shown within the dot and dash lines (Fig. 7) cut from it, is placed between the positioning surfaces 84, 85, 86 and 87 on the sleeves 45 and 83 (Fig. 6), respectively, and, thereafter, the clamp 79 may be moved from the position shown in Fig. 1 to the position shown in Fig. 6. At the completion of a previous operation on an armature blank 78, the handle 53 was manipulated to permit the spring 60 to move the clamp actuator 39 upwardly and to permit the springs 50 and 89 to move the push rods 46 and 91 away from a blank held between the sleeves 45 and 83. In other words, the cam portion 51 of the shaft 52 will be rocked to a position opposite to that shown in Fig. 6 to permit the clamp 79 to be disengaged from the clamping lug 82 and to permit the sleeve 45 to drop downwardly a sufficient distance so that the blank 78 held on the blank-holding fixture 35 may be removed therefrom. The tool-carrying tube 19 having been retracted to its upper position, as shown in Figs. 1 and 3, the apparatus is now in condition to receive a blank to be machined or turned to the configuration shown in Figs. 7 and 8. After the blank has been placed with the central portion 88 thereof in position on the positioning surfaces 84 and 85 of the sleeve 45, the clamp 79 may be moved to the position shown in Fig. 6 and while held in that position, the handle 53 will be manipulated to first move the clamp actuator 39 downwardly to permit the engagement of the clamp 79 with the clamping lug 82. After the clamp is thus positioned, continued movement of the cam 51 under the influence of the handle 53 will cause the sleeve 45

to be moved upwardly by the compression spring 50 to carry the central portion 88 of the blank 78 into engagement with the surfaces 86 and 87 of the sleeve 83. These positioning surfaces will thus tend to hold the blank against movement and the cam 51 will then become effective to compress the springs 50 and 89 and, through the action of the push rods 46 and 91, the positioning members 102, 103, 112 and 113 will be forced outwardly and into engagement with the sides 120 of the blank 78, thus to accurately position the blank with respect to the centerline of the push rods 46 and 91. Since the push rods 46 and 91 are coaxial with the tool-holding tube 19, the blank 78 held by the fixture 35 may be machined by manipulating the spider 16 to cause the tube 19 to move downwardly while it is rotating, thus to carry the tools 20-20 into engagement with the blank 78 to machine its outer surfaces. After the blank has been turned or machined by the tools 20-20, the tube may be retracted to its upper position, as shown in Fig. 3, and upon manipulation of the handle 53, the completed blank 78 may be removed from the apparatus and a new blank inserted in place thereof.

In this manner, an accurate turning operation may be performed on a blank in a drill press and the necessity of providing a lathe for this work is eliminated and the blank will be smoothly turned to have the same amount of material in both legs thereof.

What is claimed is:

1. The combination of a rotatable and reciprocable tubular tool holder having cutting tools positioned to extend inwardly on said tool holder, with a blank holding fixture for holding a blank in position to be telescoped by said tool holder, said blank holding fixture including a pair of positioning sleeves coaxial with respect to the tool holder and having positioning surfaces thereon engageable with the blank, positioning members movable radially of said sleeves for engaging a blank to position it, and means slidable in said sleeves to actuate said positioning members.

2. The combination with a tubular tool holding fixture of a blank holding fixture for holding a blank in position to be telescoped by said tool holding fixture comprising a stationary upright member, a clamp engageable with said upright member to furnish a guide surface for sleeves in the upright member, a member slidable with respect to said upright member for supporting the clamp, a pair of sleeves slidable in said upright member and carrying surfaces to engage and position a blank, and a common actuator for said clamp and said sleeves including a lever pivoted in the upright member and connected to the member slidable with respect to the upright member, and a wedging cam supported by said lever and operable to apply an actuating force to the sleeves and clamp.

3. The combination with a tubular tool holding fixture of a blank holding fixture for holding a blank in position to be telescoped by said tool holding fixture comprising a stationary upright member, a clamp engageable with said upright member, a lever fulcrumed in said upright member for actuating said clamp, a pair of sleeves slidable in said upright member and carrying surfaces to engage and position a blank, said clamp serving to aid in guiding said sleeves during the positioning of a blank therebetween, a pair of camming push rods slidable with respect to

said sleeves, a pair of positioning members associated with each push rod and slidably radially in said sleeves to engage and position a blank, and common actuating means for the clamp and push rods including a camming member interposed between said lever and one of the push rods and operable to impart force to said push rod and lever in opposite directions.

4. A blank holder for use with a tubular tool holding fixture which telescopes the blank in working on it, comprising a main support member, a pair of blank positioning sleeves slidably mounted in said member and having blank engaging surfaces thereon for engaging the body of a blank, a clamp positionable to guide said sleeves, a clamp support slidable in said member, and means for imparting relative movement to said clamp and sleeves to actuate the sleeves and position the clamp in guiding relation to the sleeves.

5. A blank holder for use with a tubular tool holding fixture which telescopes the blank in working on it, comprising a main support member, a pair of blank positioning sleeves slidably mounted in said member and having oppositely disposed blank engaging surfaces thereon for engaging the body of a blank, push rods slidable longitudinally in said sleeves, positioning members slidable transversely in said sleeves, camming surfaces on said push rods for actuating said positioning members, and means for actuating one of said push rods to apply operating pressure to said sleeves and said positioning members.

6. A turning machine comprising a tubular tool holder, an inwardly directed tool carried by said holder, a work support for an article to be worked upon extending into said tool holder, said support including elements movable radially of said tool holder to engage inner surfaces of the article to be worked, a base for supporting one end of said work support, and a bearing in the tubular portion of said tool holder for supporting the end of said work support extending therein.

7. A turning machine comprising a tubular tool holder, an inwardly directed tool carried by said holder, a work support for an article to be worked upon extending into said tool holder, said support including individual elements movable radially and axially of said tool holder to engage inner angularly disposed surfaces of the article to be worked, a base for supporting one end of said work support, and a bearing slidably mounted in said tubular tool holder for supporting the other end of said work support.

8. A turning machine comprising a fixed base, a work support on said base, said work support having individual means intermediate its ends adapted to engage inner angularly disposed surfaces of the work for supporting and positioning the work centrally of said support, a tubular tool holder centrally aligned with said support and having an inwardly directed tool, and a bearing for one end of said work support slidably mounted in said tubular tool holder.
